(57) **CLAIM**

The ornamental design for a cell phone, as shown and described.

DESCRIPTION

FIG. 1 is a front view of the design according to the invention.

FIG. 2 is a rear view of the design according to the invention.

FIG. 3 is a top view of the design according to the invention.

FIG. 4 is a bottom view of the design according to the invention.

FIG. 5 is a side view of the design according to the invention.

FIG. 6 is a sectional top view of FIG. 1 along the 6—6 line.

FIG. 7 is a sectional side view of FIG. 1 along the 7—7 line.

FIG. 8 is a sectional side of FIG. 1 along the 8—8 line; and, FIG. 9 is a perspective view of the design according to the invention.
